DOUBLE FLAP BAG AND PROCESS OF
MAKING SAMEGeorge W. Poppe, Brooklyn, N. Y., assignor to
Equitable Paper Bag Co. Inc., Brooklyn, N. Y.,
a corporation of New York

Application July 20, 1935, Serial No. 32,343

3 Claims. (Cl. 229—62)

This invention relates to paper bags and more particularly to bags having two closing flaps at the mouth thereof.

In my Patent #1,932,749 granted October 31, 5
1933, I have disclosed a bag having double flaps at the mouth thereof and in said patent the flaps are formed by slitting the edge of the bag tube.

The present invention is an improvement on the 10 type of bag shown in said patent and one of the objects thereof is to provide a bag having two closing flaps so formed that reinforcements are provided at the upper bag corners when the flaps are folded.

The invention is also an improvement on the 15 bag forming the subject matter of my application Serial No. 25,207 filed June 6, 1935 and a further object thereof is the production of a bag having the advantages set forth in my said Patent 1,932,749 and also the advantages of the bag construction disclosed in said application.

A feature of the present invention relates to a 20 paper bag having two closing flaps which flaps are cut directly from the bag walls, the base of one flap being shorter than the base of the other flap.

A further feature of the invention relates to a bag having two flaps at the mouth thereof, which flaps are prolongations of the respective bag walls, the side edges of one of the flaps extending from the upper corners of the bag to the base of the flap and converging towards the 25 center of the bag.

Further features and advantages will become 30 apparent from the following description and claims when taken in connection with the accompanying drawings in which:

Figure 1 is a diagrammatic view indicating one 35 method by which my improved bag may be produced on a bag machine of well known construction.

Figure 2 is a view of the completed bag.

Figure 3 is a view of the top portion of the bag 40 shown in Figure 2 with one of the flaps folded inside the bag.

Figure 4 is a view similar to Figure 3 but with the other flap folded on the outside of the bag.

Figure 5 is a section on the line 5—5 of Figure 4.

Figure 6 shows a bag section in which one of the flaps is slightly modified over the construction shown in Figure 3.

Figure 7 is a view similar to Figure 6 showing a further modified form of flap.

Figure 8 is a view showing a still further modification.

Referring to the drawings a tube length 45 of

which a bag is formed, is shown at the lower portion of Figure 1. This tube length comprises a plain wall 2 and a seam wall 4, the center seam 5 being in the wall 4. To complete the bag, the tube length is folded along the line a—a onto 5 the seam wall and pasted thereto. The completed bag is shown in Figure 2 with the bottom closed.

The upper or closing flaps are indicated by the 10 reference characters 6 and 8. The flap 8 is cut out of the seam wall of the bag by making cuts which extend from the upper corners of said bag wall towards the center thereof, thereby defining the side edges 10 of said flap.

In Figure 2 the side edges 10 of the flap 8 extend 15 in a diagonal direction from the upper corners of the flap to the base or fold line b—b thereof.

In Figure 3 the flap 8 is shown as having been 20 folded inside the bag and it will be noted that gussets 12 are formed at the upper bag corners due to the form of the side edges of the flap 8. When the flap 6 is folded down over the front of the bag as shown in Figures 4 and 5, these gussets form reinforcements for the upper bag corners. 25

It is not necessary that the edges of the flap 8 be formed as shown in Figure 2 so long as the flap is so cut that the base of the flap is shorter than the base of the flap 6.

In Figure 6 I have shown a slightly modified 30 form of flap in which the lower portions curve inwardly at 13 and meet the line of fold or base of the flap b—b within the bag wall 4.

In the modification shown in Figure 7 the edges 35 of the flap extend parallel to the edges of the bag for a short distance and then slant inwardly along straight lines 14—14, likewise forming a flap having a shorter base than the other flap.

In the Figure 8 construction, the side edges 15 of the flap 8 are parallel with the edges of the 40 bag but are within the bag wall 4. Again this construction results in producing a flap having a shorter base line than the other flap.

In the use of the bag it is preferred that the flap 8 be folded inside the bag as shown in Figure 45 3 and it will be readily understood that by reason of the base of this flap being shorter than the base of the flap 6 it is more easily inserted within the bag. Therefore, this construction possesses some advantages over the construction shown in 50 my Patent 1,932,749 hereinabove referred to. This construction also makes it less likely that the bag will tear at the corners when inserting the flap 8 inside the bag and therefore this construction possesses some of the advantages found 55

in the bag disclosed in my application Serial No. 25,207 above referred to.

The bag of the present invention possesses a further advantage due to the gussets 12 which 5 act to reenforce the bag corners when the flap 6 is folded down onto the seam side of the bag. It is also to be noted that the flap 6 folds on the same side as the bottom closing flap so that the front wall 2 of the bag is entirely plain, giving 10 the appearance of an envelope.

Not only does the bag in its various forms already described possess the several advantages set forth, but such a bag lends itself to a method of manufacture which is both rapid and economical.

A process or method by which this bag may be formed is shown more or less diagrammatically in Figure 1 and in order that the process may be fully understood in its application to a bag machine, reference is made to my prior Patent 20 1,798,168 granted March 31, 1931. In producing the bag of the present invention, I may use the same type of machine as illustrated in said patent without material changes.

25 It is to be understood, of course, that the paper out of which successive bags are to be formed is fed from a roll as shown and described in said patent. For convenience, I shall use as far as possible, reference characters similar to those 30 used in said patent.

The web 20 is fed over a roller indicated by 35 in said patent and either at this time or prior thereto, receives a line of paste indicated at 21 in Figure 1 of the present application. The shaft 35 52 which may be supported and rotated as described in said patent carries knives 50 which may be straight or have other shapes depending upon the type of cut which it is desired to make. In Figure 1 the knives are straight but are set 40 at an angle so that the cuts 10, while running in a general longitudinal direction, make a small angle with the edges of the web. The web passes under a former 32 supported as indicated in said patent, and the web is folded about the former to form a bag tube as is well known in 45 machines of this type. The forward edge of the former is serrated as indicated at 34. A lip knife 90 corresponding to the lip knife shown in said patent, is also provided, but this lip knife is 50 formed with a serrated edge which is curved as

shown in 36, (Figure 1) so that when the bag tube is severed transversely by the serrated edge of the former and the serrated edge of the lip knife, the top edge of the bag section presents the appearance shown in the lower portion of Figure 1. That is to say the cut produced by the lip knife extends to the bag tube edges and meets the cut produced by the edge of the former.

It is also to be noted that the line of severance 10 produced by the lip knife meets the upper ends 15 of the cuts 10. In other words the transverse cuts extend from side to side of both walls of the bag but only the transverse cut in one wall meets the ends of the cuts 10. In this respect the method of forming the present bag differs from the method described and shown in said Patent 1,798,168 in that in said patent the tube is severed along lines which connect both ends of the cuts thereby producing a bag having 20 a single flap at its upper or mouth portion.

What I claim is:

1. A bag having a front wall and a rear wall and two flaps at the mouth thereof, one of said flaps being cut from a bag wall so that the base 25 thereof is shorter than the base of the other flap thereby leaving portions of the other bag wall adjacent the side edges of said flap whereby when said shorter base flap is turned inside the bag and the other flap is folded outside, a reenforce- 30 ment of the corners of the bag is produced.

2. A bag having a front wall and a rear wall, one of said walls having cuts extending from the upper wall corners towards the center of the bag 35 wall, said cuts being of equal length and defining a flap cup from the bag wall, a portion of the wall from which the flap is cut constituting gussets at the side edges of said flap.

3. A bag having a front wall and a rear wall, cuts extending from the upper corners of one wall 40 towards the center of said wall, said cuts being of equal length and defining two flaps, one of which is cut out of one wall and the other of which is formed by the other wall and including the portions of the first said wall between the cuts and 45 the side edges of the bag, whereby when said first mentioned flap is folded inside the bag and the other flap is folded outside thereof, a reenforcement of the corners of the bag is produced.

GEORGE W. POPPE. 50
